ADJUSTABLE DISPENSING CLOSURE

Alex Limbach, Carmel, N. Y.

Application November 1, 1944, Serial No. 561,468

7 Claims. (Cl. 299—88)

This invention relates to an improved adjustable one-hand operated dispensing closure for containers of material which it is desired to dispense in highly dispersed condition.

An object of this invention is a variable closure dispenser made up of few parts of simple construction which is easy and inexpensive to manufacture and may be adjusted to produce various degrees of dispersion as well as may be sealed against operation merely by slight rotation of the dispenser relative to the container.

In accordance with this invention, a threaded member is rotatably mounted on a container neck in such manner that rotation of the member effects movement of it axially of the neck. An apertured flexible disk has one face contacting said member and has its other face concave except for a narrow rim. A flexible strip overlies the concave face of said flexible disk and is of less width than the diameter of the concave portion while being of proper length and end configuration to conform to the periphery of the flexible disk. A rigid disk overlies said flexible disk and has a central aperture, the surface of said rigid disk facing said flexible disk being slightly concave. A hemispherical bulb has its rim engaging the rim of the rigid disk and a circular band or shell encloses and connects the aforementioned members in assembled relation. The rigid disk is chamfered at its periphery to form a pair of annular chambers and is provided with grooves in both faces connecting with said annular chambers. A recess in the inner surface of the band or shell communicates with both said chambers and an aperture leads from said recess through said band to the exterior thereof.

Compression of the bulb forces the flexible strip downwardly into sealing relation to the flexible disk aperture to prevent flow therethrough and the contents of the bulb are discharged through the rigid disk grooves into the annular chambers and from these chambers into the band recess and thence through the aperture. Upon expansion of the bulb, air is drawn through the aperture in the reverse direction through the annular chamber and the rigid member grooves into the bulb. Also, liquid is drawn from the container through the flexible disk aperture and between the flexible strip straight edges and the flexible disk concave portion into one annular chamber from whence it flows through grooves in the under face of the disk into the disk aperture and thence into the bulb. By screwing the rotatable member onto the neck a sufficient extent, the flexible disk, together with the flexible strip, is bowed up to

contact the flexible strip with the concave lower face of the rigid disk closing the aperture therein to prevent liquid flow from the container into the bulb and thus render the dispenser inoperative and leak-proof. The rotary movement of the rotatable member from closed position to a position in which the flexible disk no longer contacts the end of the bottle neck varies the size of the chamber between the flexible strip and the concave face of the flexible disk and regulates the undulating movement of the flexible strip which in turn varies the volume of liquid to be dispersed.

Other objects, novel features and advantages of this invention will become apparent from the following specification and accompanying drawing, wherein:

- Fig. 1 is an elevation of a container equipped with a dispensing closure embodying the invention;
- 20 Fig. 2 is a section on the line 2—2 of Fig. 1 with the atomizer in operative position;
Fig. 3 is a section on the line 3—3 of Fig. 2;
Fig. 4 is a section on the line 4—4 of Fig. 2, and
Fig. 5 is a view similar to Fig. 2 with the atomizer in non-operating condition.
- 25 A container 10 has a neck 11 provided with an exterior thread. An interiorly threaded member 12 having a flange 12a is screwed onto the neck 11 and is preferably composed of plastic material.
- 30 By relative rotation of the neck 11 and member 12, the flange 12a is caused to assume different positions relative to the upper end of the neck 11. A disk 13 of rubber or other suitable material is of the same diameter as and rests on the upper face 35 of the flange 12a. The upper surface of the member 13 is concave except for a narrow rim portion 14 and is provided with a boss 15 having a two-diameter cylindrical passageway 16 terminating in a conical recess 17 formed in the concave surface of the disk. In commercial embodiments of the invention, the extent of concavity is much less than is shown in the drawing wherein it was necessary to exaggerate the concavity for the sake of clarity. A tube 18 of glass or other suitable material fits into the larger diameter portion of the passageway 16 and projects nearly to the bottom of the container. A strip 19 of flexible material overlies the disk 13. This strip is of less width than the diameter of the concave portion 40 of the disk 13 and is of proper length and end curvature to conform to the periphery of the disk 13. A disk 20 of the same diameter as the disk 13 and preferably composed of plastic material overlies the flexible strip 19. Both surfaces of the disk 20 are slightly concave and the disk has a
- 55

central aperture 21. A rubber hemispherical bulb 22 has an annular rim 23 resting on the disk 20. A shell or band 24 of plastic material surrounds the peripheries of the member 12, the disk 13, the strip 19, the disk 20, the rim 23 and has a flange 25 engaging the top surface of the rim 23. The shell 24 also has inwardly directed projections 26 fitting into recesses 27 in the flange 12a to attach the ring 24 to the member 12 with the remaining elements clamped therebetween. One reason for having the member 12a a separate part of the complete assembly is to permit the manufacture of all parts except the member 12 of uniform size and requiring merely that the member 12 be provided with various size threads to fit any particular type neck.

The periphery of the disk 20 is chamfered at 28 and 29 to form annular chambers 30 and 31. A circular recess 32 is formed in the inner surface of the shell 24 of proper area to communicate with both the chamber 30 and the chamber 31 and has an aperture 33 leading to atmosphere. The top and bottom surfaces of the disk 20 are provided with grooves 34 and 35 leading inwardly from the periphery of the disk and terminating short of the periphery of the aperture 21. These grooves are spirally arranged with the direction of spiral of the grooves 34 being opposed to the direction of spiral of the grooves 35. Each of the grooves increases in depth and width from its inner end to its outer end.

Fig. 2 shows the atomizer in operative condition in which the surface of the flange 12a is flush with or above the end of the neck 11. Compression of the bulb 22 forces the flexible strip 19 downwardly into sealing relation to the mouth of the recess 17 to prevent flow through the tube 18 into the container 11. The contents of the bulb are discharged through the grooves 34 and 35 into the annular chambers 30 and 31 and from these chambers into the recess 32 and through the aperture 33. The direction of flow through the chamber 29 is opposite to the direction of flow through the chamber 30 so that when the two streams reach the recess, they are caused to circle around therein in the same direction whereby thorough mixture of the air and liquid is effected prior to discharge thereof through the aperture 33. Upon expansion of the bulb 22, the flexible strip 19 is lifted toward the rigid disk 20 to form passageways 19a between the straight sides of the flexible strip 19 and the concave surface of the flexible disk 13. Air is drawn through the aperture 32 in the reverse direction into the chambers 30 and 31 and thence through the grooves 34 and 35 into the bulb while liquid is drawn from the container through the tube 18 and passages 19a into the chamber 30 and thence through the grooves 35 into the aperture 21 of the disk 20 so that the bulb contains both air and liquid. Upon compression of the bulb 22, the air and liquid in highly dispersed condition is discharged through the aperture 33.

The dispenser may be brought into inoperative condition by screwing the member 12 down into the position shown in Fig. 5. Such rotation causes the end of the container neck 11 to engage the disk 13 to bow it together with the flexible strip 19 to contact the flexible strip with the bottom face of the disk 20 to close the aperture 21 thereby preventing flow of liquid from the container through the tube 18. Compression of the bulb 22 then merely expels air from the dispenser without carrying with it any of the contents of the container. The rate of discharge of the dis-

penser is variable by rotation of the member 12 to positions intermediate those shown in Figs. 2 and 5.

The various units may be assembled without the requirement of any particular orientation of one with respect to any other. Assembly is effected merely by placing the members successively on top of each other irrespective of any orientation. As far as operation of the dispenser is concerned, the top face of the rigid disk 20 need not be made concave but it is preferred, for manufacturing reasons, to make both faces of this disk alike so that it may be assembled with the remaining parts irrespective of which way it is arranged.

I claim:

1. A device of the character described comprising a container having a neck, a member having threaded engagement with said neck, an apertured flexible disk having one face contacting said member and having its other face concave, a flexible strip overlying said other face of said flexible disk, said flexible strip being of less width than the diameter of the concave portion and of proper length and end configuration to conform to the periphery of said flexible disk, a rigid disk overlying said flexible disk and having a central aperture, the surface of said rigid disk facing said flexible disk being slightly concave, a hemispherical bulb having its rim engaging the rim of said rigid disk, a circular band enclosing and connecting the aforementioned members in assembled relation, said rigid disk being chamfered at its periphery to form annular chambers, grooves in both faces of said rigid member communicating with said annular chambers, a recess in the inner surface of said band communicating with both said chambers, and an aperture leading from said recess through said band to the exterior thereof.

2. A device of the character described comprising a container having a neck, a tubular member receiving said neck and having an annular band extending therefrom, an apertured flexible disk within said band having one face contacting said member and having its other face concave, a flexible strip within said band overlying the other face of said flexible disk, said flexible disk being of less width than the diameter of the concave portion and of proper length and end configuration to conform to the periphery of said flexible disk, a rigid disk within said band overlying said flexible disk and having a central aperture, a hemispherical bulb having its rim received in said band in contact with said rigid disk, a flange extending inwardly from said band over the bulb rim in clamping relation thereto, said rigid washer having its rim chamfered to form an annular chamber and having a slight concavity in the face thereof facing said flexible strip, grooves in said last-named disk surface leading inwardly from the disk periphery and terminating short of the periphery of the disk aperture, an aperture in said band communicating with said chamber, connections between said tubular member and neck for effecting axial movement of said member on said neck to engage the end of said neck with said flexible disk to vary the relation of said flexible strip to the opposed concave surface of said rigid disk.

3. A device of the character described comprising an apertured flexible disk having one face concave, a flexible strip overlying said flexible disk concave face and being of less width than the concave portion thereof but of proper length

and end configuration to conform to the periphery of said flexible disk, a rigid disk of the same diameter as said flexible disk overlying said flexible strip and having a central aperture, the surface of said rigid disk facing said flexible strip being slightly concave, a hemispherical bulb having its rim engaging the rim of said rigid disk, a circular band enclosing said aforementioned members and having an inwardly directed flange overlying the bulb rim, a tubular member attached to the remaining end of said band in contact with the remaining face of said flexible disk and cooperating with said band flange to clamp together the interposed members in assembled relation, said disk being chamfered at its periphery to form a pair of annular chambers, grooves in both faces of said rigid member communicating with said annular chambers but terminating short of the periphery of said rigid disk aperture, a recess in the inner wall of said band communicating with both said chambers, and an aperture leading from said recess through said band, a container having a neck projecting into said member, said neck and member having threaded connection whereby rotation of said member on said neck effects axial movement of said member on said neck to engage the end of said neck with said flexible disk to vary the relation of the flexible strip and the concave surface of said flexible disk to the concave surface of said rigid disk.

4. A device of the character described comprising an apertured flexible disk having one face concave, a flexible strip overlying said flexible disk concave face and being of less width than the concave portion thereof but of proper length and end configuration to conform to the periphery of said flexible disk, a rigid disk of the same diameter as said flexible disk overlying said flexible strip and having a central aperture, the surface of said rigid disk facing said flexible strip being slightly concave, a hemispherical bulb having its rim engaging the rim of said rigid disk, a circular band enclosing said aforementioned members and having an inwardly directed flange overlying the bulb rim, a tubular member attached to the remaining end of said band in contact with the remaining face of said flexible disk and cooperating with said band flange to clamp together the interposed members in assembled relation, said disk being chamfered at its periphery to form a pair of annular chambers, grooves in both faces of said rigid member communicating with said annular chambers but terminating short of the periphery of said rigid disk aperture, a recess in the inner wall of said band communicating with both said chambers, an aperture leading from said recess through

said band, a container having a neck projecting into said member, means interconnecting said neck and member for relative axial movement to engage the end of the neck with said flexible disk to vary the relation of the concave surface of said flexible disk and said flexible strip to the opposed concave surface of said rigid disk.

5. A device of the character described comprising an apertured flexible disk having one face concave, a flexible strip overlying said flexible disk concave face and being of less width than the concave portion thereof but of proper length and end configuration to conform to the periphery of said flexible disk, a rigid disk of the same diameter as said flexible disk overlying said flexible strip and having a central aperture, the surface of said rigid disk facing said flexible strip being slightly concave, a hemispherical bulb having its rim engaging the rim of said rigid disk, a circular band enclosing said aforementioned members and having an inwardly directed flange overlying the bulb rim, a member attached to the remaining end of said band in contact with the remaining face of said flexible disk and cooperating with said band flange to clamp together the interposed members in assembled relation, said disk being chamfered at its periphery to form an annular chamber, grooves in the under face of said rigid member communicating with said annular chamber but terminating short of the periphery of said rigid disk aperture, and an aperture through said band communicating with said chamber.

6. In combination, a container having a neck, 35 a dispensing closure having a portion receiving said neck, means interconnecting said neck and closure for movement of said closure axially of said neck, means in said closure for withdrawing liquid from said container and discharging the 40 liquid in highly dispersed condition including valve means for preventing return flow of liquid to said container, and means in said closure cooperating with said valve means upon movement of said closure on said neck to restrict flow of liquid from said container into said closure.

7. In combination, a container having a neck, a dispensing closure having a portion receiving said neck, a threaded connection between said neck and closure, means in said closure for withdrawing liquid from said container and discharging the liquid in highly dispersed condition including valve means for preventing return flow of liquid from said closure to said container, and means in said closure cooperating with said 55 valve means upon axial movement of said closure on said neck to restrict flow of liquid from said container into said closure.

ALEX LIMBACH.
